METHOD OF MANUFACTURING HEAT EXCHANGE DEVICES

Paul F. Schoen, Dearborn, Mich., assignor to Bohn Aluminum & Brass Corporation, Detroit, Mich., a corporation of Michigan

Original application June 17, 1939, Serial No. 279,690. Divided and this application February 1, 1940, Serial No. 316,803

1 Claim. (Cl. 29—157.3)

This invention relates to a method of manufacturing heat exchange devices.

A primary object of the invention is to provide a structure of improved economy and efficiency, and this object is accomplished by construction of the heat exchanger from tubing extruded from aluminum or other suitable material. The tubing is extruded with fins on both the inner and outer diameters, and the tubing is twisted to give the fins a spiral form, which increases the heat-exchange efficiency and improves the physical properties of the tubing. If the tubing is to be bent in forming a heat-exchange unit, the part to be bent is kept in more pliable condition by not twisting it, and the external fins are removed prior to bending.

These and other objects and advantages of the invention will become apparent as the description proceeds.

While preferred forms of the invention are disclosed herein for purposes of illustration, various changes may be made in the method without departing from the spirit of the invention as herein set forth and claimed.

This application is a division of my application Serial No. 279,690, filed June 17, 1939, which claims the article resulting from the method.

In the drawing:

Fig. 1 is a plan view of a heat exchange device embodying the invention.

Fig. 2 is a section on line 2—2 of Fig. 1.

The invention is illustrated in connection with a unit for application to a wall or ceiling of a cold storage room, although obviously the novel features may be used in heat exchange devices for other purposes.

The cooling unit illustrated consists of a single length of tubing 10, which is extruded with a plurality of external fins 11 and with a plurality of internal fins 12. This tubing is preferably extruded from commercially pure aluminum, although other suitable materials may be used.

At places where the tubing is to be bent, such as at 13, the outer fins are sheared off to prevent any interference with the bending operation.

As the result of the extruding operation, the fins 11 and 12 are originally aligned with the longitudinal axis of the tubing. In order to give the fins of the tubing a spiral shape the length of the tubing to be spiraled, for example the straight run 14, is twisted while under tension. This is preferably done by applying clamps to the outside of the tube at the points 15 and 16, and rotating one of the clamps while pulling it away from the other clamp. This operation maintains the tube preferably straight and gives an even and uniform spiral shape to the fins, the pitch of the spiral depending on the number of turns given to the movable clamp.

The run 14 is preferably twisted while the entire piece 10 is a straight length, and it is to be understood that this first twisting operation does not twist the tube beyond the point 16, so that the internal fins at the place 13 have not been spiraled.

The next operation is to bend the tube at the place 13. In order to prevent collapse of the tube and of the internal fins a "mouse" formed of a plurality of flexible elements, such as wires, is drawn into the tubing to the place 13, and the tube is then bent in the desired direction.

The next run 15 of the tubing is then spiraled, and the bend 17 is next formed, these operations being repeated until the unit illustrated is formed. As an alternative method the different runs of the tubing can be spiraled while the tubing 10 is in one straight piece if suitable arrangements are made to keep the sections where the bends are to be made in their original un-twisted condition.

The external fins are removed at the ends 18 and 19 in order to provide a smooth tube adapted for connection with the tubing of a refrigeration system. The internal fins may also be removed at the ends 18 and 19 if desired.

Among the advantages of the above construction are the fact that the twisting of the tube to spiral the fins elongates the edges of the fins, which were extruded as thin as possible, thus thinning them and increasing their efficiency for heat conduction. At the same time the tubing itself is shortened and thickened, thus increasing the safety factor on the tube. The spiral fins serve as very stiff ribbing against bending of the tube sections, and the bending of the fins in spiraling serves to cold-work the fins, increasing their hardness against external damage.

The spiral fins make very efficient contact with air currents, since air moving across the tube is directed around the spiral fins, making wiping contact with the tube and the fins. The spiral shape of the fins avoids any pockets in which condensation might collect.

The runs 14, 15, etc., need not be parts of a single tube, but can be separate pieces connected together or to a header by suitable fittings.

I claim:

The method of producing a heat exchange device which comprises extruding a length of tubing having internal and external longitudinal fins, giving the fins on certain parts of the tubing a spiral form relative to the tubing, removing the external fins from the ends of the tubing and from certain parts intermediate the ends, and bending the tubing at said intermediate parts.

PAUL F. SCHOEN.
